(57) **CLAIM**

The ornamental design for a sight for use on firearms, as shown and described.

DESCRIPTION

FIG. 1 is a front elevation view of a first embodiment of the sight for use on firearms.

FIG. 2 is a perspective view of the first embodiment showing the invention.

FIG. 3 is a front elevation view of the first embodiment showing the forward portion of the invention.

FIG. 4 is a perspective view of the first embodiment showing the forward portion of the invention.

FIG. 5 is a front elevation view of the first embodiment showing the rearward portion of the invention.

FIG. 6 is a perspective view of the first embodiment showing the rearward portion of the invention.

FIG. 7 is a front elevation view of a second embodiment of the sight for use on firearms.

FIG. 8 is a perspective view of the second embodiment showing the invention.

FIG. 9 is a front elevation view of the second embodiment showing the forward portion of the invention.

FIG. 10 is a perspective view of the second embodiment showing the forward portion of the invention.

FIG. 11 is a front elevation view of the second embodiment showing the rearward portion of the invention; and,

FIG. 12 is a perspective view of the second embodiment showing the rearward portion of the invention.

The broken lines are for purposes of illustration only and form no part of the claimed design.

The portions of the design provided with surface shading have been shaded to represent that the surface exhibits an area of contrasting appearance relative to any surrounding structures.
